BY
Robert F. Beck
ATTORNEY

same for use under various conditions of service. Moreover, it is not indispensable that all the features of the invention be used conjointly since they may be employed advantageously in various combinations and subcombinations.

It is obvious that the invention is not confined to the herein described use therefore as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. A shoulder frame adapted to be removably encased within a sheath carried within the shoulder of a garment and comprising a pair of substantially semi-elliptical members connected together at their marginal arcuate edges; said members being transversely curved and defining upper and lower members with the latter adapted to embrace the sloping shoulder of a wearer; each of said members having a transverse edge face spaced from the other between its ends to define an opening for effecting communication of a chamber, disposed between said members, and the atmosphere and for positioning said lower member outwardly and downwardly with respect to said upper member when the latter is disposed in substantial horizontality and said edge faces in substantial vertical alignment to thus elevate the shoulder of a garment and simulate the appearance of a square natural shoulder.

2. A shoulder frame adapted to be removably encased within a sheath carried within the shoulder of a garment and comprising a pair of substantially semi-elliptical members connected together at their marginal arcuate edges; said members being transversely curved and defining upper and lower members with the latter adapted to embrace the sloping shoulder of a wearer; each of said members having a transverse edge face spaced from the other between its ends with the transverse curvatures of said members, at said edge faces, being generated from different points and of substantially the same radii whereby said lower member extends outwardly and downwardly with respect to said upper member when the latter is disposed in substantial horizontality and said edge faces in substantial vertical alignment to thus elevate the shoulder of a garment and simulate the appearance of a square natural shoulder; and a reinforcing rib disposed centrally between said members and extending longitudinally therebetween; said members and said rib being structurally integrally connected to each other at their jointures whereby to provide a unitary frame structure.

3. A shoulder frame adapted to be removably encased within a sheath carried within the shoulder of a garment and comprising a pair of substantially semi-elliptical members connected together at their marginal arcuate edges; said members being transversely curved and defining

upper and lower members with the latter adapted to embrace the sloping shoulder of a wearer; each of said members having a transverse edge face spaced from the other between its ends with the transverse curvatures of said members, at said edge faces, being generated from different points and of substantially the same radii whereby said lower member extends outwardly and downwardly with respect to said upper member when the latter is disposed in substantial horizontality and said edge faces in substantial vertical alignment to thus elevate the shoulder of a garment and simulate the appearance of a square natural shoulder; and a reinforcing rib disposed centrally between said members and extending longitudinally therebetween, said members being structurally integrally connected together at their jointures to provide a unitary frame structure.

4. In combination, a shoulder frame comprising a pair of substantially semi-elliptical members connected together at their marginal arcuate edges; said members being transversely curved and defining upper and lower members with the latter adapted to embrace the sloping shoulder of a wearer; each of said members having a transverse edge face spaced from the other between its ends to define an opening for effecting communication of a chamber, disposed between said members, and the atmosphere and for positioning said lower member outwardly and downwardly with respect to said upper member when the latter is disposed in substantial horizontality and said edge faces in substantial vertical alignment to thus elevate the shoulder of a garment and simulate the appearance of a square natural shoulder; and a fabric sheath removably encasing said frame and adapted to be detachably secured within the shoulder of the garment.

5. A shoulder frame adapted to be incorporated within the shoulder of a garment and comprising a one-piece body formed with a chamber and being of a substantially semi-elliptical shape in plan and fashioned with upper and lower convex and concave faces extending over and beneath said chamber, respectively, said body being of a substantially cuneiform configuration in central longitudinal sectionality and formed with a substantially crescent-shaped transverse face provided with an opening through which said chamber communicates with the atmosphere, said concave face adapted to embrace the sloping shoulder of a wearer to dispose the mediacy of said convex face in a substantial horizontal plane and said transverse face in a substantial vertical plane to elevate the shoulder of the garment disposed over said frame for simulating the appearance of a square natural shoulder.
